UNITED STATES PATENT OFFICE.

CHARLES J. HORDIS, OF JEANNETTE, PENNSYLVANIA.

ENVELOP.

1,069,549.

Specification of Letters Patent.

Patented Aug. 5, 1913.

Application filed August 21, 1912. Serial No. 716,276.

To all whom it may concern:

Be it known that I, CHARLES J. HORDIS, a citizen of the United States, residing at Jeannette, in the county of Westmoreland and State of Pennsylvania, have invented new and useful Improvements in Envelops, of which the following is a specification.

This invention relates to envelops and has for an object to provide means for securely sealing the envelop so as to prevent the same from being opened without detection.

Another object of the invention is to provide an improved form of fastening for the envelop whereby the separate flaps of the latter can be securely connected together without use of an adhesive.

In the drawing forming a portion of this application, and in which like letters of reference indicate similar parts in the several views: Figure 1 is a view of the blank of which the envelop is formed. Fig. 2 is a plan view of the envelop showing the sealing flap closed. Fig. 3 is a section on line 3—3 of Fig. 2. Fig. 4 is a perspective view of the cap. Fig. 5 is a perspective view of the socket member. Fig. 6 is a section on line 6—6 of Fig. 2.

The envelop is preferably constructed of a single blank of material which is provided with a front portion 1, side flaps 2, a relatively long end flap 3 which is substantially co-extensive in length with the portion 1, and a relatively short sealing flap 4. The flaps 2 are preferably of rectangular configuration and passing therethrough and through the flap 3 is a fastening device such as an eyelet A, as shown in Figs. 2 and 6 of the drawings.

A stem 5 is extended through the flaps 2 and 3, the inner end of the stem being riveted or upset as at 6 against a washer 7, which latter bears against one side of the innermost flap 2. The stem is provided with an integral flange 8 which is disposed outermost and against the innermost flap 2. In this manner the stem effectually serves as a retainer to positively hold the flaps 2 and 3 of the envelop securely connected together and without the use of an adhesive.

50 The outer end of the stem 5 is provided with a substantially conical head 9. The sealing flap 4 is provided with a resilient socket member 10 whose jaws 11, while being slightly springy are extremely fragile,

whereby they will become broken when excessive pull is applied to the sealing flap. The jaws 11 are curved as at 12 toward each other and their extremities extend parallel to the plane of the inner walls of the head 9 of the stem 5 whereby after the 60 socket member has been operatively associated with the head of the jaws 11 will so engage against the head that when excess pull is applied to the sealing flap the terminals of the jaws will be strained and as a 65 consequence the seal will be broken. In this manner it is evident that the destruction of the seal will offer evidence that some one not authorized has tampered with the envelop while in transit.

The socket member 10 is provided with a continuous flange 13 which is spaced from an adjacent portion of the member so as to define therewith an annular groove 14. The cap member 15 of the fastener is secured at 75 16 to the sealing flap 4. As shown the cap is provided with bendable tongues 17 that are adapted to ride against the curved surfaces 12 of the jaws 11 and to engage in the annular groove 14 of the socket member 80 whereby the latter and the cap are secured together to the sealing flap. The cap member forms a complete housing so as to cover the locking extremities of the jaws 11 and to protect the locking head 9. The flaps 2 and 85 3 are connected together by an eyelet A or the equivalent thereof so as to insure against lateral separation of the flaps at any points between the opposite ends of the envelop.

I claim:

An envelop including folded flaps and a sealing flap, a locking stem securing the folded flaps together and provided with a conical-head, a socket member located on the inner side of the sealing flap and including a member having a rolled edge presenting an annular concavity and springy fragile jaws curved into the inner walls of said concavity, the said jaws being adapted to receive the head of the locking stem there-through whereby portions of the jaws are invited under their inherent elasticity into engagement with a portion of the head, a protecting cap located exteriorly of the sealing flap and adapted to house the locking terminals of the jaws and the head of the locking stem when the latter is operatively associated with the former, and

tongues carried by the cap and adapted to be extended through the sealing flap and to be engaged against the curved jaws and to be deflected into the concavity through their engagement with the jaws and operating to hold the socket member operatively connected with said sealing flap.

In testimony whereof I affix my signature in presence of two witnesses.

CHAS. J. HORDIS.
